Henry Houston
Attn: J. L. Paulson

Des. 1743

Samuel Sailor, of Philadelphia, Penn.
Letters Patent No. 1743, dated, May 24, 1863.

The schedule referred to in these Letters Patent and making part of the same

To all whom it may concern:

But known that I, Samuel Sailor, of Philadelphia, County of Philadelphia, State of Pennsylvania, have invented or produced a new and original design for a Picture Frame; and I do hereby declare . . . the accompanying Drawing, with the following explanation of the same to form a full, clear and exact description of the said Design.

The Figure in the annexed drawing represents a front view of my Design, for a Picture Frame.

The body of the frame is oval in form, and consists of plain mouldings with an ornamented edging, the latter being concealed at the lower portion of the frame by the flags a.a.

At the bottom of the frame is a shield b, on each side of which is a spring c, the upper end of these springs overlapping the lower portion of the flags d.a.

On the top of the frame is a medallion containing a bust in bas relief.

This medallion is surrounded with an eagle, and has on each side a scroll and foliated ornament d.

I claim the ornamental figures and forms represented in and by the accompanying drawing, the whole forming an ornamental design for a picture frame.

In testimony whereof I have signed my name to this specification in the presence of two subscribing witnesses.

W. H. Bressel
